BRUSH

Rebecca O. Pope, Mountain Lakes, N. J.

Application March 26, 1954, Serial No. 29,710

Term of patent 14 years

(Cl. D9—2)

To all whom it may concern:

Be it known that I, Rebecca O. Pope, have invented a new, original, and ornamental Design for a Brush, of which the following is a specification, reference being made to the accompanying drawing forming a part hereof, in which:

Fig. 1 is a side view of a brush embodying the invention; and

Fig. 2 is a similar side view at right angles to Fig. 1.

I claim:

The ornamental design for a brush, as shown.
